UNITED STATES PATENT OFFICE.

NATHL. A. BOYNTON, OF BOSTON, MASSACHUSETTS.

HOT-AIR FURNACE.

Specification of Letters Patent No. 9,573, dated February 8, 1853.

To all whom it may concern:

Be it known that I, NATHANIEL A. BOYNTON, of Boston, in the county of Suffolk and State of Massachusetts, have invented certain new and useful Improvements in Hot-Air Furnaces for Warming Buildings or the Apartments Thereof; and I do hereby declare that the same are fully described and represented in the following specification 10 and the accompanying drawings, letters, figures, and references thereof.

Of the said drawings Figure 1 denotes a front elevation of my improved furnace. Fig. 2 is a vertical and central section taken 15 through the fire place and ash pit doorways. Fig. 3 is a side elevation of the ash pit box, the fire pot, the melon shaped dome or smoke chamber, the wheel radiator and its revolving cap discharge tube. Fig. 4 is a 20 horizontal section of the fire place dome or smoke chamber. Fig. 5 is a horizontal section of the wheel radiator. Fig. 6 is a vertical transverse section of the said radiator. Fig. 7 is a side view of the vertical stem 25 valve thereof. Fig. 8 is an end view of the said valve. Fig. 9 is an external elevation of spherical shaped hub for the wheel radiator or one made with a horizontal stem valve. Fig. 10 is a horizontal section of the 30 same hub exhibiting a top view of its valve and valve stem. Fig. 11 is a vertical cross section of the spherical hub taken through two of the depressions of the valve and two corresponding arm openings of the hub. Fig. 12 is a similar vertical cross section 35 taken at right angles to the plane of section of Fig. 11.

In the said drawings A represents the fire pot or chamber for holding the fuel 40 while in a state of combustion. It is a hollow cylinder or other proper shape having a grate B at its lower part and made to rest over an ash pit or chamber C, whose entrance passage is seen at D and as having a door E. Resting directly on and above the fire pot is what I term the melon shaped smoke chamber or dome F, which is a hollow metallic vessel made externally in the shape, 45 or closely approximating thereto, of a musk melon or cantaloup, that is to say, it is corrugated or made serpentine in a horizontal direction, as seen in Fig. 4, and is curved in a vertical direction or on its sides, so that the corrugations shall diminish as they 50 recede upward or downward from the middle part toward the top or bottom, where they

terminate in vertical circular, or other proper shaped rings a, b, by which the smoke chamber is joined to the fire pot, and the wheel radiator G to be hereinafter described. 60 Such a construction of the smoke dome of the fire pot enables me to obtain a greatly reduced capacity of it under a great extent of internal as well as external surface, a large part of the internal surface being 65 brought into such a relation with respect to the column of flame and smoke arising from the fuel that the said column directly impinges against it.

A dome or smoke chamber made in the 70 above form will be found to be a very decided improvement over the common cylindrical or frustro-conical chambers such as are made either with or without fluted sides.

The volatile products of combustion pass 75 from the smoke chamber into the hollow hub H of the wheel radiator G. I term such radiator a wheel radiator because it is made with a hollow rim or annulus I, a hollow cylindrical or barrel shaped hub H 80 (open at top and bottom), and hollow spokes L, L', M, M' which open both into the hub and rim. Horizontally across the middle of the hub is a plate or partition N (see Fig. 5) which has two sectoral openings c, d, made through it and two sectoral depressions or concavities e, f, which latter may be said to be a prolongation of the lower half of the arms M, M', as they open 85 into the said arms and the upper half part 90 of the hollow hub. A vertical stem valve O of a peculiar construction rests and moves on the plate or partition N. It is shaped like such partition, but has its position reversed thereon, or is arranged on it as seen 95 in the drawings. It is attached to the lower part of a vertical stem P that proceeds through the top of the hub and the cap or hood R and has a crank arm Q on its upper end, the said crank arm being jointed to a 100 slide rod S. By taking hold of the slide rod and moving it the valve may be turned through an arc of ninety degrees. Now when the valve is made to cover the orifice c d, the smoke and volatile products of combustion will be caused to pass from the lower half of the hub and through the pipes or arms L, L', and into the hollow rim I and from thence pass through the pipes M, M' 105 into the upper half of the hub or the space 110 over the valve. When the valve is turned around ninety degrees from such position it

will close the inner ends of the arms M, M' and open the orifice c, d, thereby causing the smoke and volatile products to pass directly upward through the openings c, d, without first coursing through the arms and rim of the radiator.

As to the radiator, the fire pot and melon shaped smoke chamber are placed within a chamber U into which cold air passes and from which after being heated therein it escapes through proper pipes leading, respectively, to such apartments as it may be desirable to warm, the column of air which rises in the said chamber is brought into contact with the external surfaces of the hub, the spokes and the rim of the radiator, and is thereby warmed to great advantage, much more so than is the case where a ring radiator is used with vertical pipes leading into it from the smoke chamber.

As it is often desirable to make use of a valve having a horizontal stem, I construct the valve and its hub as seen in Figs. 9, 10, 11, and 12. The hub is a hollow sphere or portion thereof at that part q of it which receives the arms or is joined to them or has their orifices m, n, o, p, and the whole hub is made high enough to allow the valve to freely turn within it. In combination with such a spherical shape in whole or part I make the valve circular and with two angular sectoral depressions x, r, extending below one face of it and in opposite directions from its center. The opposite side of the valve has two similar depressions s, t, which are placed or arranged between the first two x, r. The valve turns on journals at u, v, and has a stem w extended horizontally from it. The outer

edges of the valve are disposed in the surface of a sphere so as to allow the valve to be turned within the spherical part of the hub. Now when the valve is disposed in a horizontal position the smoke will pass through the arms and rim of the radiator, but when it is turned up into a vertical position the smoke will escape directly up through the hub and not first pass through the arms and rim.

Having thus described my invention I do not claim a hollow ring radiator placed over and made to communicate with the chamber of combustion, but

What I do claim is—
The above described hollow "wheel radiator" made with a hollow rim, hollow spokes, a hollow hub (open at top and bottom), and a valve and valve seat so made and applied to the hub that when the valve is closed it shall cause the heat and volatile products of combustion to pass through one or more of the arms and into and through the hollow rim, and thence out of the said rim through the other arm or arms and into the hub and over the valve, and also so that when the said valve is opened the heat and volatile products of combustion may pass directly up through the hub without first circulating through the hollow arms and rim, substantially as specified.

In testimony whereof I have hereto set my signature this twelfth day of February, A. D. 1852.

N. A. BOYNTON.
